UNITED STATES PATENT OFFICE.

OVE L. GAMMELL, OF ATTLEBORO, MASSACHUSETTS, ASSIGNOR TO SMITH & CROSBY,
OF ATTLEBORO, MASSACHUSETTS, A FIRM.

FASTENING DEVICE.

Application filed March 3, 1926. Serial No. 91,904.

My invention relates to fastening devices adapted for concealed embodiment in the shells of ornamental chains for personal adornment, such as bracelets, garters, necklaces, and articles of like character.

The essential objects of my invention are to provide a fastening device adapted for substantially concealed embodiment in the chain, and at either the ends or at an intermediate portion of the latter. Further objects are security against accidental disengagement of parts, facility of manipulation, and inexpensiveness of construction.

To the above ends essentially my invention consists in such parts and in such combinations of parts as fall within the scope of the appended claims.

In the accompanying drawings which form a part of this specification

20 Figure 1 is a side elevation of an ornamental chain in the form of a bracelet or garter wherein my fastening device is embodied in an intermediate portion of the chain,

25 Figure 2, an enlarged similar elevation of the medial portion of the chain,

Figure 3, a similar front or top elevation of the same,

30 Figure 4, a section on line 4—4 of Figure 3 showing the fastener members fully interengaged,

Figure 5, a section on line 5—5 of Figure 4,

35 Figure 6, a section similar to that of Figure 4 but showing the fastener members after release,

Figures 7 and 8, sections on lines 7—7 and 8—8 respectively of Figure 4, and

40 Figures 9, 10 and 11, detail views of the latch member, catch member, and the spacing member respectively.

Like reference characters indicate like parts throughout the views.

45 The body 15 of the chain herein shown comprises a series of units 16, pivotally connected to each other. Each unit consists of a shell alone, or of an outer shell and an enclosed slide, according to whether the chain is nonexpansible or expansible. In this instance the ends of the chain carry hooks 17 adapted to engage a watch or ornament. As herein shown two adjacent units 19 and 20

of an intermediate portion of the chain consist merely of rectangular tubes or shells for containing the constituent parts of my 55 fastening device, and serve as the terminal units of the chain.

Each of the shells 19 and 20 comprises a front 21, a back 22, and sides 23, whose outer ends carry pivot members 24 connecting the 60 shells to the ends of adjacent units. The pivot members comprise in this instance inwardly directed fingers 25 loose in tubes 26. These shells are transversely rectangular and have open adjacent ends. In the shell 19 is 65 mounted a U shaped compressible latch member of a fastener comprising a flat base 27 fixed by solder to the back 22 of the shell and projecting through the open end of the same, an end loop 28 comprising two 70 curved arms 29; and a resilient tongue 30 which presses against the front 21 of the shell and is compressible towards the plate 27. Intermediate its length the tongue 30 is rearwardly offset as at 31 forming a terminal offset portion 32 also projecting beyond the end of the shell 19 and provided with a cavity or hole 34. Near the offset portion of the tongue 30 is an integral lug 36 covered by a cap 37. The lug and cap form 80 a fingerpiece which projects through cavities 39 in the adjacent ends of the front walls 21 of the shells 19 and 20. The base 27 is provided with a longitudinal guide slot 40 in alignment with the tongue, which slot has 85 a retracted intermediate portion formed by oppositely disposed projections 41 formed in the base extending into an intermediate portion of the slot and forming a retracted narrow passage 42. The projecting end of the 90 base has upturned lateral guard lugs 43.

The shell 20 is adapted to receive the projecting portions of the tongue 30 and base 27, and has fixed by solder to its front or top 21 a lining plate 45 having in this instance upon one end a rearwardly directed wall 46, integral with a lateral flange 47 parallel with the plate and bearing against the shell back 22. Formed from the material of the plate 45 is an inclined rearwardly 95 directed catch 48 located in the path of the tongue and adapted to snap into the cavity 34 when the adjacent ends of the shell are in contact.

It is evident that sufficient rearward or downward pressure of the finger piece 37 will release the tongue from the catch 48 and permit the shells to be manually disconnected. It is desirable that the detachment of the parts be not effected accidentally, and to prevent this the following blocking means is employed. This consists of a spacing plate 50 slidably mounted between the base 27 and tongue of the entrant member and longitudinally movable from a point between the offset portion of the tongue and the base 27 to a position at one side of said offset portion. In detail the plate 50 is in the form of a yoke comprising a body 51 and resilient compressible arms 52. The latter have integral lateral ears 53 projecting through longitudinal slots 54 in the sides 23 of the shell 19. By means of these ears 53 the operator may manually slide the plate into blocking position opposite the offset 32 or into unblocking position at one side of the offset. To assist the plate during its travel there are provided upon the rear faces of the arms 52 integral lugs 56 which register in the guide slot 40.

In order to insure that the plate 50 be not accidentally longitudinally moved, the lugs 56 upon the free ends of the arms 52 are normally spaced from each other a greater distance than the width of the passage 42 in the guide slot. Hence when it is desired to shift the plate from blocking to unblocking position the ears 53 may be compressed to bring the lugs 56 towards each other sufficiently to permit them to pass between the projections 41 and then release the ears. Thus the plate 50 is locked in either blocked or unblocked position. In Figure 4 wherein the member 50 is shown in advanced or blocking position it will be observed that the thickness of the member 50 is such as to prevent the offset portion 32 of the tongue from freeing itself from the catch 48 when the finger piece 37 is depressed. In Figure 6 the member 50 is shown moved to one side of the offset 31, which permits the portion 32 to be depressed sufficiently to pass beyond the plane of the catch 48 and permit the shell 20 to be withdrawn and wholly disengaged. Herein the latter shell is shown slightly withdrawn.

The lugs 43 form a guide or guard to prevent the end of the front wall 21 of the shell 20 from being accidentally inserted below or in the rear of the tongue portion 32 when the shell 20 is moved towards the shell 19. After the fastening members are engaged the terminal shells 19 and 20 conceal the former, and the shells are not noticeably different in appearance from the remainder of the chain. When, as herein shown, the terminal shells are in an intermediate portion of the chain it is obvious that any ornament or watch carried by the chain hooks

need not be detached to remove the chain from the wearer's body. The arms 29 of the loop 28 is found preferable to a single integral loop when the terminal shells are short, for the reason that when the entrant member is short the arm construction is less apt to set in bent position.

It will be noted that while the members of this fastener cannot be separated while the slide 50 is in forward or blocking position, nevertheless it is possible to bring the two parts of the fastener into engagement with each other even when the block 50 is in blocking or advanced position, which is a noticeable convenience in enabling the wearer to attach the parts without any attention to the position of the member 50.

I claim:

1. In an ornamental chain including terminal shells, a compressible entrant fastening member in one shell, a catch in the other shell engageable with the entrant member when the fastening member is noncompressed, and a member slidably mounted in the first shell engageable with the fastening member to block the compression of the entrant member.

2. In an ornamental chain including terminal shells, a compressible entrant fastening member in one shell, a catch in the other shell engageable with the entrant member, a spacing member slidably mounted in the first shell adapted to block the compression of the entrant member in one position and to unblock the entrant member in a second position, and means in the first shell for locking the spacing member in either blocked or unblocked position.

3. In an ornamental chain, a pair of housing shells, a compressible substantially U-shaped fastening member comprising a flat base fixed in the shell, spaced curved arms integral with one end of the base within said shell, a broad tongue integral at one end with the arms and provided near its free end with a cavity, and a catch in the second shell in the path of the tongue adapted to register in the cavity.

4. In an ornamental chain comprising connected terminal shells, said shells being provided in their adjacent edges with cavities adapted to register with each other, a compressible fastening member comprising a base fast in one shell and adapted to extend into the other shell, a resilient tongue upon the base also adapted to extend into the second shell and provided with a cavity, a catch in the second shell registerable in the last mentioned cavity, and a lug integral with the tongue adapted to project through the first mentioned cavities when the shells are engaged.

5. In an ornamental chain including terminal shells, a compressible entrant member comprising a base fixed in one shell, a

loop, and a yielding tongue in front of the base provided with a rearwardly offset projecting end portion provided with a cavity adapted to extend into the other shell, a catch in the second shell adapted to register in the cavity, and a spacing plate slidably mounted in the first shell between the base and tongue and movable into and out of contact with the offset portion of the tongue to block or release the tongue.

6. In an ornamental chain including terminal shells, a compressible entrant fastening member comprising a base fixed in one shell, a tongue yieldingly supported upon one end of the base having an offset projecting end portion provided with a cavity adapted to enter the other shell, a catch in the second shell in the path of the offset portion adapted to snap into the cavity, the first shell being provided with longitudinal slots, a spacing plate in the first shell comprising a body and compressible arms movable into and out of engagement with the

offset portion of the tongue, and lateral ears on the arms extending loosely through the slots.

7. In an ornamental chain including terminal shells, a compressible entrant fastening member comprising a base attached to one shell provided with a guide slot having a retracted intermediate portion, and a longitudinally disposed tongue yieldingly supported upon the base and having an offset end portion provided with a cavity, a catch in the second shell in the path of the offset portion of the tongue registerable in the cavity, the first shell being provided with longitudinal slots, a spacing plate comprising a body and compressible arms slidably mounted in the first shell, lateral ears upon the arms registerable in the longitudinal slots, and projections upon the arms registerable in the guide slot.

In testimony whereof I have affixed my signature.

OVE L. GAMMELL.
